UNITED STATES PATENT OFFICE.

MAURICE N. CONNOR, OF BUFFALO, NEW YORK, ASSIGNOR TO FRANK W. CARTER, OF BUFFALO, NEW YORK.

FIRE-EXTINGUISHING APPARATUS.

1,272,012.

Specification of Letters Patent.

Patented July 9, 1918.

Application filed January 29, 1913. Serial No. 744,870.

To all whom it may concern:

Be it known that I, MAURICE N. CONNOR, a citizen of the United States, residing at Buffalo, in the county of Erie and State of New York, have invented certain new and useful Improvements in Fire-Extinguishing Apparatus, of which the following is a specification.

This invention relates to improvements in fire extinguishing apparatus generally, and particularly to chemical apparatus used upon and in conjunction with parts of a motor driven vehicle.

More specifically the invention relates to a suitable tank mounted upon the chassis of a motor vehicle and provided with an internal agitator and means for supplying water and carbon dioxid to the tank, together with means for operating the agitator during the formation of the solution of water and gas, and other means for heating the gas as it passes from the drum to the tank to prevent freezing in the expansion of the gas, this heating device being applied upon the exhaust of the motor vehicle.

Further the invention resides in certain details of construction and combination of parts hereinafter set forth in the following description, drawings and claims.

Referring to the drawings, Figure 1 is a side elevation of the forward portion of a motor vehicle equipped with my apparatus; Fig. 2 is a vertical longitudinal section; Fig. 3 is a sectional view of the heater showing part in elevation; Fig. 4 is a horizontal longitudinal section; Fig. 5 is an enlarged end view showing the controlling apparatus; Fig. 6 is an enlarged end view taken upon the line 6-6 of Fig. 4, showing the chambers in the head; and Fig. 7 is a sectional view on the line 7-7 looking to the right and showing the relation of the overflow and the discharge pipe, together with the relation of the gas inlet.

In carrying out the invention any preferred form and construction of parts may be employed so long as they possess the necessary characteristics, but I have shown one arrangement in the drawings which is highly effective in operation, and in such embodiment 1 represents the frame of a motor vehicle which is mounted upon the usual wheels 2. Supported upon the frame

1 in any suitable manner and horizontally 55 disposed is a tank 3 of sufficient size to hold a large volume of liquid. This tank extends transversely of the frame and on the head end is provided with suitable controlling valve mechanism and gas supply mechanism which will be described.

The tank 3 is provided with a suitable bottom 4 carrying a bearing 5 supporting an agitator shaft 6 provided with agitators 7 having diametrically disposed blades. 65 There are three agitators, and they are spaced throughout the tank and are so arranged that they will thoroughly agitate the liquid therein. The mechanism for supporting the forward or head end of the 70 shaft will be described later.

The tank 3 is preferably lined with sheet copper 8 on all sides and the bottom and the head end is provided with a suitable opening 9 extending through the steel tank and the lining. In this opening is mounted a suitable cylindrical connection 10 having a flange 11 conforming to the interior of the head and provided with openings 12. This connection 10 and the flange 11 are held in 80 place by a suitable ring 13 threaded into the cylindrical portion of the connection. When the parts are drawn up tight by the ring 13, the interior of the tank is then flooded with solder so as to form a solder 85 joint 14, as shown in Fig. 4. This solder extends from the central ridge 15 out to meet the head as shown in this figure and the solder passes down through the openings 12 and firmly secures the parts in place, 90 thus avoiding leakage. The object of the openings 12 is to provide round cross sections of solder connecting the accumulated solder 14 and the solder which passes between the lining and the flange. In this 95 way the connection 10 is held against rotation. Threaded on to the connection 10 is a head 16. A suitable packing 17 is arranged between this head and the end of the connection 10 to prevent leakage. 100

The head 16 is provided with three internal chambers 18, 19 and 20. The first chamber 18 is connected by a suitable opening 21 on the inside of the head with a pipe 22 extending into the tank and down toward the 105 bottom as shown. This pipe forms the liquid inlet and discharge from the tank. This chamber 18 is also provided with a

radially disposed opening 23 outside of the tank, and this opening is connected by a nipple 24 to a T-shaped valve 25 which is provided with a valve seat 26 as shown in Fig. 5. This valve seat has co-operating with it a valve 27 manipulated by the usual valve mechanism which needs no description. The valve seats in the bottom portion of the T and does not interfere in any way, as shown in Fig. 5, with the passage of liquid above the valve. This valve 27, the valve seat and the pipe 24 serve as a main supply for the tank in initially filling the same, and also to allow a stream to flow from pipe 30 directly to the hose connection 45 for quenching the fire and to simultaneously divert a portion of the main supply stream into the tank for filling the same. One side of the T of this valve is connected to a pipe 28 leading to a valve 29 in turn connected to a pipe 30 mounted in a support 31 secured to the head and terminating at its lower end in a suitable hose connection 32. This hose connection is of the usual size for receiving fire hose and it may also receive a reduced hose connection 33 as shown. The opposite side of the T-shaped valve 25 is connected to a pipe 34 leading to a valve 35 connected to a suitable cross connection 36 for a purpose to be described.

The chamber 19 is connected by a suitable opening 37 with a pipe 38 extending up into the tank to a point about four inches from the upper part thereof, as shown. This pipe 35 forms an overflow pipe for establishing the level of the liquid and may also serve as a discharge for expanded gas from the tank. This chamber communicates by a radially disposed pipe 40 with a valve 41 leading to a downwardly extending discharge 42, as shown in Fig. 5, connected to a three-way cock 43 in turn connected to two pipes 42 and 44, the former leading downward and serving as a discharge, and the latter being secured in the downwardly extending opening of the cross connection 36, the connection opposite to the pipe 34 being provided with a hose reel connection 45 and opposite to the pipe 44 being provided with a suitable cap 46.

The chamber 20 communicates with a pipe 48 extending within the tank and inclined downward so as to project the inflowing gas toward the rear end of the tank. This gas chamber communicates by a radially disposed pipe 49 with a valve 50 connected to a T 51 having a connection to the right, as shown in Fig. 5, with a suitable regulator valve 52. This regulator valve is of ordinary construction and is provided with the usual gage 53 and a check valve 54 is arranged between this regulator valve and the connection 51. The remaining end of the T is connected to a pipe 55 leading to a valve 56. This latter connection is utilized for dis-

charging free gas directly from the reducing valve. Connected to the reducing valve 52 is a pipe 57 leading through a heater casing 58 through a packing 59 within the casing and forming a part of a heater coil 60 wound upon the exhaust pipe 61 of the engine of the motor vehicle. The pipe 62 leading from this coil connects directly with the valve mechanism 63 of the gas container 64 which is of ordinary construction and is a commercial product.

From the foregoing, it will be seen that the chamber 18 forms a water receiving and water discharge chamber; that the chamber 19 forms an overflow and expanded gas discharge, while the chamber 20 serves as a gas receiving and gas discharging chamber establishing communication from the gas supply in the tank.

The head 16 is still further provided with a centrally disposed opening 65, as shown clearly in Figs. 2 and 4, for receiving packing arranged about a shaft 66. This packing is drawn up tight by means of a gland ring 67 and a nut 68. The inner end of the shaft 66 is provided with a socket 69 which receives a squared end 70 of the shaft 6. This connection is loose so that the shaft may be moved longitudinally. The portion of the socket member toward the head forms a sealing member and the corresponding portion of the head a seat for receiving the sealing member and sealing the joint about the shaft 66. The outer end of the shaft is threaded to receive a hand nut 72 and the extreme outer end is provided with a suitable handle or crank 73 utilized in rotating the shaft.

In manipulating the entire mechanism, assuming that the tank is empty of all liquid, and further assuming that the gas container is full of gas, the valve 35 is closed and the valves 27 and 29 are open, thus permitting water from the main to enter through these valves into the chamber 18 and thence through the pipe 22 to the bottom of the tank. As soon as water overflows through the pipe 38, the chamber 19 and the pipe 42, the operator knows that the tank is filled, the valve 41 having been previously opened. The operator then closes the valves 41, 27 and 29, opens the valve from the gas container, seeing to it that the valve 56 is closed and that the valve 50 is open. The gas is then admitted to the tank through the pipe 49 into the chamber 20 through the pipe 48 into the water. In the meantime the nut 68 is in the position shown in Fig. 4, and the operator rotates the agitator shaft 6, thus agitating the water and causing a rapid formation of the solution of CO_2 and water. This operation is continued until a gage 74 communicating with the chamber 19 indicates the proper pressure when the tank is thoroughly charged. This operation con-

sumes about two minutes and when the gas discharge from the container 64 is closed, the machine is ready for operation, and if immediate use is necessary, the operator 5 opens the valves 27 and 35, permitting the gasified water to discharge through the discharge service hose upon the fire, the valve 29 being closed as above stated. If a second filling of the tank is necessary in 10 service, the operator leaves the valve 27 open, discharges the gas from the tank through the connection 41, opens the valve 29 to supply water to the discharge hose and divert a sufficient quantity therefrom under 15 the valve 27 to fill the tank. This diversion takes place without any appreciable variation in the stream of the service discharge hose, and takes a very short period of time. When this has been accomplished the operator 20 closes the valve 27 without interfering with the supply of water from the hydrant to the fire and completes the operations already described in the charging of the tank with gas. When the water is completely 25 charged, the valve 29 is closed and the valve 27 open, then gasified water is supplied to the fire.

The apparatus also permits the discharge of free gas to the fire, and this is accomplished by closing the valve 27 or the valve 35 turning the three-way cock 43 and opening the valve 41 to permit a flow of gas from the upper part of the tank to the pipe 44 from whence it will pass to the cross connection 36 and out through the service hose connection 45, the cap 46 being in place.

Having described my invention, I claim:—

1. In fire extinguishing apparatus, a tank horizontally disposed, a head at one end 40 comprising a water inlet and discharge chamber, an overflow and gas outlet chamber, and a gas inlet chamber, a discharge connection leading from the water inlet and discharge chamber, a pipe leading from 45 said chamber into the tank near the bottom thereof, a connection leading from the overflow and gas discharge chamber, a pipe leading from this chamber to a point near the top of the tank, a connection leading 50 from the gas inlet chamber to the outside of the head, a pipe from the same chamber for discharging its gas downward into the

tank, and means for supplying gas to the gas connection.

2. Fire extinguishing apparatus, comprising 55 a tank, a liquid supply pipe, a discharge hose connection communicating with said supply pipe and with the tank, a valve controlling the flow of liquid from the supply pipe to the tank, a valve located between 60 the tank and the discharge hose connection, and means for conducting gas directly from the tank to the discharge hose connection.

3. Fire extinguishing apparatus, comprising 65 a tank, a liquid supply pipe, a discharge hose connection communicating with said supply pipe and with the tank, a valve controlling the flow of liquid from the supply pipe to the tank, a valve located between the tank and the discharge hose connection, a 70 gas supply pipe communicating with the tank, a pipe for conducting gas from the tank to the discharge hose connection, and a valve in said gas conducting pipe.

4. Fire extinguishing apparatus, comprising 75 a tank, a liquid supply pipe communicating therewith, a gas supply pipe also communicating therewith, a service hose connection, a gas discharge pipe communicating with said connection and having one end open 80 in the upper portion of said tank, and means for conducting liquid directly from the liquid supply pipe to the service discharge hose connection.

5. Fire extinguishing apparatus, comprising 85 a tank, a liquid supply pipe communicating therewith, a gas supply pipe also communicating therewith, a service hose connection, a gas discharge pipe communicating with said connection and having one 90 end open in the upper portion of said tank, means for conducting liquid directly from the liquid supply pipe to the service discharge hose connection, and a single valve controlling the flow of liquid from the 95 liquid supply pipe to the tank or from the tank to the service discharge hose connection.

In testimony whereof I affix my signature in presence of two witnesses.

MAURICE N. CONNOR.
